—DESIGN.

W. A. HOLMAN.
ALBUM LEAF.

No. 17,233.

Patented Apr. 5, 1887.

UNITED STATES PATENT OFFICE.

WILLIAM A. HOLMAN, OF PHILADELPHIA, PENNSYLVANIA, ASSIGNOR TO
A. J. HOLMAN & CO., OF SAME PLACE.

DESIGN FOR AN ALBUM-LEAF.

SPECIFICATION forming part of Design No. 17,233, dated April 5, 1887.

Application filed March 5, 1887. Serial No. 220,881. Term of patent 3½ years.

To all whom it may concern:

Be it known that I, WILLIAM A. HOLMAN, a citizen of the United States, and a resident of Philadelphia, Pennsylvania, have invented and produced a new and original Design for Album-Leaves, of which the following is a specification, reference being had to the accompanying illustration.

In the illustration, A is the space in the album-leaf in which the inserted picture or card is displayed; B, a fay riding the crescent moon, the space about being interspersed with stars; C, a bat with spread wings; D, a cluster of "flower-bells" and grass, with other pendent flowers; E, a cluster of "cat-tails" and a spider's web with a fly entangled in the meshes thereof and a spider dependent therefrom; F,

a marshy pond with blades of grass, water-lilies, and a bank of bordering land; G, a cluster of flowers and grass with "toad-stools;" H, winged "fays" attacking a snail "rampant;" I, a winged fay emerging from an open crescent; J, shoots of bushes with pendent flowers.

Of course slight variations may be made in the details of my general design while its main features are preserved.

What I claim as new is—

The design for album-leaves, substantially as shown, upon the leaf surrounding the space for displaying the card.

WILLIAM A. HOLMAN.

Witnesses:

WM. H. CARSON,
GEORGE E. BUCKLEY.
